INVENTOR.

BY (M. Harpman)
ATTORNEY.

UNITED STATES PATENT OFFICE

CARL W. GLAESER, OF YOUNGSTOWN, OHIO

BOTTLE PROTECTOR

Application filed April 13, 1931. Serial No. 529,713.

This invention relates generally to a casing to be used as a protector for nursing bottles. It is, of course, understood that the protector may be utilized on other bottles in order to protect the same from accidental breaking.

The principal object of this invention is to provide a casing made of elastic material preferably rubber and made in one piece.

A further object of the invention is to provide a casing provided with a depended peripheral flange at its lower end.

A still further object is to provide a plurality of bottom portions forming a seat for the bottle when placed within the casing.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

The invention will be better understood by reference to the following description taken in connection with the accompanying drawing, wherein:

Figure 1 is a side elevation of the device with part broken away showing a bottle placed within the casing.

Figure 2 is an end view of the device with part broken away.

Figure 3 is a detail view of Figure 1 with parts broken away showing the manner in which the bottle is inserted in the casing.

Referring more particularly to the drawing the numeral 1 designates a casing which is preferably constructed of rubber and is moulded in shapes and sizes suitable to hold round or other shaped bottles. In Figure 1 a bottle 2 is shown in its correct position within the casing 1. It will also be seen that this casing 1 is provided with a depended peripheral flange portion 3 at its lower end. Directly above this depended peripheral flange 3 there is positioned a plurality of bottom portions 4 and 5. These bottom portions 4 and 5 are relatively thicker than the casing

1. (See Figs. 2 and 3). It will be seen that the bottom portions 4 are larger than the bottom portions 5.

In inserting a bottle 2 within the casing 1 the operation in doing this is as follows: The operator takes the casing 1 and bends back the bottom portions 4 and 5. The bottle 2 is placed upon a stand and the operator slips the casing 1 down over the bottle 2 until the bottle is in a position shown in Figure 1. The bottom portions 4 and 5 are now allowed to spring back into position holding the bottle 2 within the casing 1.

It will also be seen by referring to the drawing that there are provided horizontal ribs 6 on the interior of the casing 1 and vertical ribs 7. The object of these ribs 6

and 7 is to provide a cushioned means for the casing 1 and also to provide means for more efficiently holding the heat within the bottle 2.

It is obvious that there are provided air cushioned spaces 8 that prevent rapid radiation from the bottle.

This device should prove advantageous as a safety means as well as providing means for retaining heat in a bottle within a casing.

With this device the probability of securing an injury through broken glass is practically removed should, for any reason, a breakage of the bottle 2 within the casing 1 be caused.

What I claim is:

In a device of the class described, a casing made of rubber, a lower depending flange formed on said casing, a plurality of bottom portions consisting of two oppositely disposed bottom portions, two other oppositely disposed bottom portions of relatively smaller size than the first mentioned bottom portions, said bottom portions being relatively thicker than said casing, a plurality of horizontal ribs formed on interior of said casing, a plurality of vertical ribs formed on interior of said casing, thus forming a plurality of air cushioned spaces on the interior of said casing, substantially as described for the purpose set forth.

In testimony whereof, I affix my signature.

CARL W. GLAESER. 100
